UNITED STATES PATENT OFFICE.

JACOB WEIDMANN, OF PATERSON, NEW JERSEY.

FILTER.

SPECIFICATION forming part of Letters Patent No. 625,001, dated May 16, 1899.

Application filed June 17, 1898. Serial No. 683,732. (No model.)

To all whom it may concern:

Be it known that I, JACOB WEIDMANN, a citizen of the United States, residing at Paterson, in the county of Passaic and State of New Jersey, have invented certain new and useful Improvements in Filters; and I do hereby declare the following to be a full, clear, and exact description of the invention, such as will enable others skilled in the art to which it appertains to make and use the same.

The object is to provide a filter which will rapidly and effectively purify a large volume of water and thoroughly eliminate therefrom all gross impurities, together with all deleterious matter, which in use will not become clogged with the retained matter, which may be easily cleansed and kept in condition for practically continuous use, and which will be simple of construction and of great durability in use.

The invention consists in the novel construction and combination of parts of a filter, as will be hereinafter fully described and claimed.

In the art in which this invention is particularly intended for use—namely, in connection with silk-dyeing—an enormous quantity of water is used daily, and it is absolutely essential that this water shall be pure and free from any dirt, coloring-matter, slime, or impurities of any kind. When it is taken into consideration that the quantity of water used runs up into the millions of gallons per diem, it will be apparent that the filters must be of very large capacity to handle such a volume of water and to thoroughly cleanse and purify the same for use.

As is well known in all manufacturing cities where the refuse water and other materials from the mills, factories, and the like are discharged directly into the river or stream upon which the city may be located, this stream inevitably becomes so foul and contains so much filth and poisonous animal and vegetable matter as to kill all animal life.

In my case the silk-dyeing works are located at the lower extremity of the city of Paterson, New Jersey, and consequently the water from the Passaic river that passes my works is in the foulest possible condition, so much so that even a small quantity when taken into a glass presents the appearance of

filthy ditch-water. It is upon this supply of water that I have to depend for furnishing pure and clean water to be used in my works. 55

Ordinary filters, such as are in common use, even if constructed on a large scale, are absolutely useless for my purpose, as in a very short time the impurities contained in the water will clog up the filters and render them 60 inoperative. The desideratum is not only to have a supply of clean and pure water, but to have it in such volume as may be required, so that under all conditions—that is to say, no matter how foul the water may be, even if 65 additionally foul, as from heavy rains—the supply will always be equal to the demand.

As a result of experiments extending over a number of years I have found that by employing as a filtering medium finely-divided 70 coke and excelsior perfectly satisfactory results are attained; but even in the use of the excelsior a particular kind must be employed, and as an excelsior best suited for my purpose I have found that produced from the 75 wood of the tulip-tree, known commercially as "white wood," to be most effective, inasmuch as the same is very soft and open-grained, thus presenting the requisite absorbent qualities, and by reason of its fuzzy, 80 furry, filamentoid, or pile surface it acts to catch and retain slime and the finest impurities, whereas excelsior produced from other woods, particularly from a hard or close-grained wood, will not possess the requisite 85 retaining and absorbent qualities necessary to accomplish the desired result.

I have found that the best results are attained by dividing the inflowing volume of foul water—that is to say, the water coming 90 directly from the source of supply—and directing it through two filters, so that instead of the first filter catching the bulk of the impurities, which would tend rapidly to clog the filter, and thus necessitate its frequent cleaning, these impurities will be divided between 95 two filters, resulting not only in avoiding clogging the filters, but also permitting a greater discharge of water to the succeeding filters.

In carrying my invention into effect I provide in this instance five stands of filters, each stand comprising four filters arranged in a row, and between each stand is arranged a pressure equalizer and distributer, the func-

tion of which, as its name indicates, being to cause a practically uniform pressure and discharge through the whole stand of filters with which it connects. The value of this feature 5 will be readily appreciated when it is taken into consideration that it would be practically impossible to pack four or more filters with such evenness and precision that the discharge of water from all will be the same, as 10 it will be inevitable that some will discharge with greater rapidity than others, so that in effect if the filters were simply connected up in series and one filter discharged into another there would be an uneven discharge at 15 the exit end of the series, the force of discharge fluctuating with the capability of the succeeding filters to handle the water passing through them. To obviate this, the pressure equalizer and distributor is employed in connection with each stand of filters, and by this arrangement the pressure and discharge are kept up throughout the whole series, and at the exit end, where the final distributor is arranged, a constant and practically unvarying 20 flow of water will be discharged.

25 To render the filters as effective in cold weather as in warm, I may provide steam-coils to encircle the filters and the pressure equalizers and distributors or to be arranged between them, as may be most effective or convenient, so that when the filters cease work for the night there will be no danger of the water therein becoming frozen, thus rendering the plant inoperative.

30 35 In the accompanying drawings, forming a part of this specification, and in which like letters of reference indicate corresponding parts, I have illustrated one form of embodiment of my invention, it being understood 40 that other forms of embodiment may be employed without departing from the spirit of the same.

45 In the drawings, Figure 1 is a view in side elevation displaying somewhat diagrammatically a filtering plant embodying my invention. Fig. 2 is a view in plan showing more particularly the connection between the filters and the pressure equalizers and distributors.

50 Referring to the drawings, and more particularly to Fig. 2 thereof, I have shown in this instance five stands of filters, each stand comprising four filters, the filters in each stand being out of communication with each 55 other, each stand being designated, respectively, by A, B, C, D, and E, and arranged between each stand of filters is a pressure equalizer and distributor, (designated, respectively, by A², B², C², D², and E².) The filters 60 A, B, C, D, and E are constructed, preferably, of boiler-iron, and each is provided near its top with a door a, through which access may be had to the interior of the filter for the purpose of filling the same with the filtering 65 medium and near its bottom with a manhole a², by which to permit cleansing of the lower portion of the filter. Each filter is also pro-

vided with an escape-pipe a³, carrying a valve a⁴, this pipe connecting with the sewer or other place of discharge, and being designed 70 to permit of the filters being emptied when desired for the purpose of cleansing or repair. At a point near the bottom of each filter is arranged a screen a⁵, which rests upon the legs or uprights a⁶, secured to the bottom of 75 the filter, and arranged near the top of each filter is a similar screen a⁷, bearing against legs a⁸, projecting downward from the top of the filter, the function of the lower screen a⁵ being to support the filling of coke a⁹ and 80 that of the upper screen to keep the filling of excelsior a¹⁰ out of contact with the top of the filter and also to prevent any escape of the excelsior through the discharge-pipes. In this instance the filling of coke occupies 85 about two-thirds of the height of the filter between the two screens and the excelsior the remaining third; but it is to be understood that these proportions may be varied without departing from the spirit of my invention. 90

As all the filters are constructed in the manner described, a description of the operation of one will serve for the whole.

The water is supplied to the first pressure equalizer and distributor A² through a pipe 95 f, connecting with a tank F, supported in this instance upon the roof of the building containing the filters, and at such elevation as to insure the proper fall to give the requisite head to the water, the water to the tank 100 being supplied from a pipe G, connecting with a force-pump, (not shown,) drawing the water from the supply—in this instance, the river. The pipe f is provided with a valve f², by which the supply of water may be regulated or cut off. The pressure equalizer and distributor A² is connected with the two stands of filters A B by branch pipes a¹¹ and b, these pipes entering the filters below the screens a⁵. Each branch pipe is provided 110 with a valve a¹² and b², respectively, so as to permit either stand of filters being cut out from the pressure equalizer and distributor. The supply of water from the pressure equalizer and distributor A² is divided, one half 115 passing up through the series of filters A and the other up through the series of filters B and out of the top of each filter through a discharge-pipe a¹³ and b³, respectively, to the second pressure equalizer and distributor B². 120 It will thus be seen that the first pressure equalizer and distributor has one supply-pipe and eight branch pipes, and that the second pressure equalizer and distributor B² has eight supply-pipes, this being caused by the 125 connection therewith of the eight discharge-pipes leading from the filters A and B. Each discharge-pipe is provided with a valve, as a¹⁴, by which to cut out from the pressure equalizer and distributor the filter discharging therethrough. The pressure-equalizer 130 B² has four branch pipes b⁴, each carrying a valve b⁵, these pipes entering the stand of filters C, and from the top of the filters extend

discharge-pipes c , carrying a valve c^2 , and connecting with the pressure equalizer and distributer C^2 , the same order being kept up to the final pressure equalizer and distributer E^2 , which is provided with the discharge or outlet pipe e , leading to the place of use. By the arrangement of valves on the discharge-pipes and on the branch pipes any one or more of the filters may be cut out from the series for the purpose of cleansing or repair.

While the supply of water to the filters is in this instance shown as being from the bottom portion of the filter and the discharge from the top, it is to be understood that these conditions may be reversed—that is to say, the feed of water may be from the top of the filters and the discharge from the bottom—without departing from the spirit of my invention. Of course when the relative positions of the feed and discharge pipes are changed it will also be necessary to change the relative positions of the filtering mediums—that is, to place the excelsior at the bottom of the filter and the coke at the top. It is also to be understood that the number of stands of filters and the number in each stand may be changed to a greater or less number if found necessary or desirable, and that instead of having the last equalizer and distributer E^2 discharge to the place of use the pipe e upon this distributer may connect with another stand of filters, thus further to purify the water, and as such arrangement will be obvious an illustration of it is deemed unnecessary.

To obviate the possibility of the filters becoming inoperative in cold weather, as from the water freezing either in the filters themselves, the discharge-pipes, or in the pressure equalizers and distributers, I may employ steam-pipes to inclose the filters, as indicated by H in Fig. 2, wherein only the first stand of filters A is shown in connection with these steam-pipes, this merely to avoid confusing the drawings, it being understood that each stand of filters is similarly inclosed by steam-pipes; or instead of the arrangement shown the coils may extend only on two sides of the filters, the exact arrangement being a mere matter of mechanical choice, the object being, as stated, to prevent any freezing of the filters in extremely cold weather.

Having thus fully described my invention, what I claim as new, and desire to secure by Letters Patent of the United States, is—

1. The combination with a plurality of filters, of a pressure equalizer and distributer, substantially as described.

2. The combination with a plurality of filters, of a pressure equalizer and distributer, and means for cutting off communication be-

tween either of the filters and the pressure equalizer and distributer, substantially as described.

3. A filter having a filtering medium comprising a body of crushed coke superimposed by a mass of excelsior, screens for keeping the coke and the excelsior out of contact with the ends of the filter, a pressure equalizer and distributer discharging below the under screen, and a discharge-pipe arranged above the upper screen, substantially as described.

4. A filtering plant comprising stands of filters disconnected from each other, a pressure equalizer and distributer arranged adjacent to each stand, a source of supply connecting with the first pressure equalizer and distributer, connections between the pressure equalizer and distributer and the filters of the first two stands, pipes discharging from the first two stands of filters into a second pressure equalizer and distributer, connections between this latter pressure equalizer and distributer and a third stand of filters, and so on throughout the system, the last pressure equalizer and distributer connecting with the place of use, substantially as described.

5. A filtering plant comprising stands of filters disconnected from each other, a pressure equalizer and distributer arranged adjacent to each stand, an overhead source of supply connecting with the first pressure equalizer and distributer, connections between the pressure equalizer and distributer and the filters of the first two stands, pipes discharging from the first two stands of filters into a second pressure equalizer and distributer, connections between this latter pressure equalizer and distributer and a third stand of filters and so on throughout the system, the last pressure equalizer and distributer connecting with the place of use, and means for cutting out any one or any stand of filters in the series without interfering with the operation of the others, whereby to permit cleansing or repair, substantially as described.

6. The combination with a plurality of filters and a pressure equalizer and distributer coöperating with each of the filters, of heating means for preventing the water either in the filters or in the pressure equalizer and distributer from freezing, substantially as described.

7. The combination with a plurality of filters and a pressure equalizer and distributer, of heating-coils, substantially as described.

In testimony whereof I affix my signature in presence of two witnesses.

JACOB WEIDMANN.
